[57] CLAIM

The ornamental design of a child safety seat for vehicles, as shown and described.

DESCRIPTION

FIG. 1 is a perspective view of the child safety seat for vehicles embodying my new design viewed from above and from the front;

FIG. 2 is a front elevational view thereof;

FIG. 3 is a side elevational view thereof;

FIG. 4 is a rear elevational view thereof; and

FIG. 5 is a bottom plan view thereof.

The side of the chair not shown is substantially a mirror image of the side shown in FIG. 3.

FIG. 1

FIG. 2

FIG. 3

FIG. 4

FIG. 5
